CLAIM

The ornamental design for a retrofit container vent as shown and described.

DESCRIPTION

FIG. 1 is a front perspective view of a retrofit container vent, showing my new design;

FIG. 2 is a front view thereof;

FIG. 3 is another front perspective view thereof;

FIG. 4 is a front perspective view of the design of FIG. 1 installed in the wall of a container;

FIG. 5 is another front view thereof; and,

FIG. 6 is another perspective view thereof.

The broken line depictions illustrate environmental structure and form no part of the claimed design.
